CLAIM

I claim the ornamental design for a vapor product packaging, as shown and described.

DESCRIPTION

FIG. 1 is a top, front, right perspective view of an embodiment of the claimed design in a first configuration; FIG. 2 is a top, front, right perspective view thereof in a second configuration;

FIG. 3 is a top, front, right perspective view thereof in a third configuration;

FIG. 4 is a top plan view thereof in the first configuration;

FIG. 5 is a right side elevation view thereof;

FIG. 6 is a left side elevation view thereof;

FIG. 7 is a front elevation view thereof;

FIG. 8 is a rear elevation view thereof; and,

FIG. 9 is a bottom plan view thereof.

The broken lines in the drawings are for illustrative purposes only and form no part of the claimed design.
